CLAIM

The ornamental design for a neck pack organizer, as shown and described.

DESCRIPTION

FIG. 1 is the front perspective view of a neck pack organizer showing my new design;

FIG. 2 is the front elevational view thereof;

FIG. 3 is the rear elevational view thereof;

FIG. 4 is the left side view thereof;

FIG. 5 is the right side view thereof;

FIG. 6 is the top plan view thereof; and,

FIG. 7 is the bottom view thereof.

In FIGS. 2-5, the neck cord has been cut away for the convenience of illustration.
